UNITED STATES PATENT OFFICE

127,998

DESIGN FOR A DINNER PLATE

John Le Graffe, Los Angeles, Calif.

Application May 1, 1940, Serial No. 92,077

Term of patent 14 years

To all whom it may concern:

Be it known that I, John Le Graffe, a citizen of the United States, residing at Los Angeles, in the county of Los Angeles and State of California, have invented a new, original, and ornamental Design for a Dinner Plate, of which the following is a specification, reference being had to the accompanying drawing, forming a part thereof.

Fig. 1 is a top plan view of a dinner plate, showing my design.

Fig. 2 is a vertical section taken through the dinner plate, illustrated in Fig. 1, on the line 2—2.

I claim:

The ornamental design for a dinner plate, substantially as shown.

JOHN LE GRAFFE.
